[57] CLAIM

The ornamental design for audioconference telephonic terminal set, as shown and described.

DESCRIPTION

FIG. 1 is a bracket associated perspective view of an audioconference telephonic terminal set showing my new design (a) with the dialing unit spaced apart from the parent terminal base, and (b) with the receiver unit partially unfolded;

FIG. 2 is a side elevational view thereof;

FIG. 3 is a top plan view thereof;

FIG. 4 is a side elevational view taken on the line 4—4 of FIG. 3 of the other two sides; and

FIG. 5 is a bottom plan view thereof.

FIG. 1

FIG. 2

FIG. 3

FIG. 4

FIG. 5
